UNITED STATES PATENT OFFICE.

CURT HILSCHER, OF CHEMNITZ, GERMANY.

PROCESS OF MANUFACTURING STOCKINGS UPON THE FLAT HOSEY FRAME.

Application filed March 1, 1923. Serial No. 622,125.

To all whom it may concern:

Be it known that I, CURT HILSCHER, a citizen of the German Republic, residing at Chemnitz, Germany, have invented certain new and useful Improvements in Processes of Manufacturing Stockings upon the Flat Hosiery Frame (for which I have filed an application for patent in Germany on the 2nd of June, 1922), of which the following is a specification.

Upon the flat hosiery frame specially two kinds of stockings are produced, viz: those with English foot and those with French foot.

Preference is given to stockings with English foot on account of the sole seams being arranged at the sides of the foot instead of upon the sole as with the French stockings. The French stocking presents however the advantage of the better shape of the toe and of being without lateral seams at the toes.

This invention relates to a process for the production upon the flat hosiery frame of a stocking with English foot and French toe.

In order that the invention may be clearly understood, I shall proceed to describe hereafter the same with reference to the accompanying drawing, wherein:

Fig. 1 shows diagrammatically the first phase of the working method and

Fig. 2 the second phase of the same.

Fig. 3 shows the foot of a stocking made according to the improved working method.

The following is the working method for the production of a stocking.

The leg *a* with the heel parts *b* and the upper part *c* of the foot (Figs. 1 and 3) is first made in the manner known from stockings with English foot only with the difference that the usual working method extends only to the beginning of the toe of the foot at *e*. The toe, instead of being knitted after the manner known as an English toe is knitted after the manner known as French toe, the latter having the breadth *u* of the leg (Fig. 1) instead of the breadth *c* commonly used for an English toe.

The beginning of the toe which consists of several rows of loops from *d'* to *d* is composed of three parts, viz: the middle part *c* and the two side parts *d'* and *e'*. The French toe consisting of one part *f* over its entire breadth, the mode of manufacturing the same being known, joins the last row of loops at *d*.

After the toe has been finished the fin-

ished part of the hose is removed from the legging frame and transferred to a sole frame. This transfer is effected in such a manner that the toe *f* is turned down and set on the frame needles along the lines *d-e* in such a manner that the lateral ends *d* of the toe are placed the one meeting the other (Fig. 2). The rows of loops *d', e'* (Fig. 1) which were necessary for the setting-on are now undone so that only the row *e d e* (Fig. 2) exists. This row *e d e* the breadth of which corresponds with that of the upper part *c* of the foot serves merely as start for the making of the sole part *g* known from stockings with English foot which extends up to the line *h* (Fig. 2) and which is widened several times before it is finished in order to produce the so-called foot wedge.

The manufacturing of stockings upon the hosiery frame is thus finished. The stocking must now be closed along the parts *i*, *h* and *e* indicated in Fig. 3 in thick lines and along the bottom of the toe by sewing or stitching so that between the heel and the toe of the foot the side seams *h-e* known from socks with English foot and the well-known French toe be produced the seam of which does however not form an extension of the seams *h-e* as is usually the case with the English foot and are consequently not situated sideward of the toes but below the same upon the sole.

The working method described presents further the advantage that only about one third of the sole machines is necessary compared with the number of sole machines required at present and that consequently less persons are required.

I claim:

Process of manufacturing a stocking upon the flat hosiery frame consisting in working, after the production of the legs, heel parts, and foot upper, of several setting-on rows in the breadth of the French toe, in producing the French toe in continuation of said setting-on rows, in removing the stocking from the frame needles, in setting-on upon the frame needles the parts of the toe which project laterally over the foot upper and in using the set-on parts as beginning for the sole part which has to be worked in the same breadth as these parts.

In testimony whereof I affix my signature.

CURT HILSCHER.
